UNITED STATES PATENT OFFICE.

REINHOLD SCHOLZ, OF NEW YORK, N. Y.

SELF-OILER FOR SLIDING MUSICAL INSTRUMENTS.

Application filed December 3, 1925. Serial No. 72,945.

The main object of this invention is to provide a lubricating device adaptable for use on a trombone for oiling the reciprocating slide.

5 Another object is to provide a container upon fixed tubes of the trombone which are receptive of the slide. The container is provided with a cylinder which is divided into several compartments, one normally locked 10 from the other by a spring projected trap disk which when depressed, allows the small quantity of lubricating liquid to enter into a lower compartment from which it is drained directly by the parts lubricated.

15 The above and other objects will become apparent in the description below, in which characters of reference refer to like-named parts in the drawing.

20 Referring briefly to the drawing, Figure 1 is a perspective view of a trombone, showing the lubricating devices mounted in their respective positions.

25 Figure 2 is a longitudinal sectional elevational view, showing the lubricating structure in detail.

Figure 3 is a cross sectional view taken on line 3—3 of Figure 2.

Figure 4 is a top plan view of Figure 2.

30 Referring in detail to the drawing, the numeral 10 indicates the horn from which the sound of the musical instrument proceeds. This horn communicates with a tube 11 which extends rearwardly from the horn and has a semi-circular curve 12 at its rear 35 end from which curve, the length of tubing projects. The tubes 11 and 13 communicate with each other and the horn thru the semi-circularly curved portion 12 and are aligned in a vertical plane. Extending parallel to the tube 13 on a horizontal plane is a short pipe 14 which is of the same dimensions as the tube 13 and is connected with the latter by bars 15 which also serve as elements for holding the trombone in the hands. The 40 rear end of the pipe 14 has a mouthpiece 16 affixed thereto and the forward ends of the tube 13 and pipe 14 are open to permit the ready insertion of the parallel extending tubes 17 and 18 of a reciprocating slide.

45 The tubes 17 and 18 of the slide are mutually joined by a semi-circularly curved tubular portion 19, and near the curved portion, a brace bar 20 is provided for reinforcing the alignment of the tubes 17 and 18. Near the ends of the tube 13 and pipe 14 where the tubes 17 and 18 of the slide

are inserted into said tube 13 and pipe 14, the lubricating mechanism is mounted. This lubricating mechanism is used in duplicate on each instrument and comprises a 60 longitudinal container having a roof 21, sides 22 and 23, and an inclined end wall 24, and a vertical opposite end wall 25. The lower edges of these end and side walls are brazed to the body of the pipe 14 and tube 65 13 and form an enclosed chamber 26 into which lubricating oil is adapted to be filled. A trap is provided within the chamber 26 by constructing a cylinder 27 in which a plurality of openings 28 are formed near its 70 upper end. Said cylinder is provided with an internal flange 29 midway of its length within the bore and below the openings 28. A trap disk 30 has its peripheral edge seated upon the surface or face of the flange 29 75 and is normally retained in such seating contact therewith by a coil spring 31 which rests upon the periphery of the tube or pipe to which the lubricating device is attached.

Wherever the device is to be used as a lubricating container, the body of the pipe or tube is perforated by a conical opening 32 which passes thru the wall of the tube or pipe within the confines of the chamber 26 directly beneath the cylinder 27 and spring 80 31. By providing the flange and seating the trap disk 30 on its face, an upper compartment 33 and a lower compartment 34 is provided. These compartments are intercommunicating but are normally sealed one 85 from the other by the trap disk which is loosely slidable in the compartment 34 by virtue of its being of smaller diameter than the bore of the compartment 34 in the cylinder. A lug is provided on the roof 21 of the 90 casing directly above the cylinder 27. This lug is provided with a threadable hole in which a threaded shank 35 is engaged. The shank is provided with a head 36 which may be manipulated by the fingers and extends axially downward, its lower end passing thru the compartment 33 and being adapted to contact with and depress the trap disk 30 against the tension of the 95 spring 31.

100 This lubricating device is particularly adaptable to musical instruments having reciprocating parts, such as a trombone. Wherever one tubular member is adapted to reciprocally receive another member, the 110 casing may be mounted on the outer member to lubricate the bearing surfaces between

both. In the case of a trombone, casings are mounted on the pipe 14 and tube 13 after the conical openings 32 are drilled in the walls of these members at desirable positions. 5 The casing consisting of the roof 21, side walls 22 and 23, and end walls 24 and 25, is mounted upon these members in such position that the lower compartment 34 in the cylinder 27 communicates with the openings 32. The casing is sealed in a leak-proof manner upon the tubes or pipes of the musical instrument by brazing or some similar operation. In order to fill the chamber 26 of the casing, the shank 35 is removed 10 from the threaded opening in the lug situated on the casing by manipulating the head 36. The lubricating liquid trickles thru the opening into the upper compartment 33 of the cylinder and then drains into the chamber 26 thru the openings 28. The chamber 34 into which the oil must first pass in order to lubricate the parts desired, is sealed while the casing is being filled by the trap disk 30. When desiring to lubricate the parts or sliding 15 surfaces, as it is in this case, the shank 35 is rotated so that it is moved longitudinally downward and depresses the trap disk 30 away from the flange 29. The lubricating liquid will then flow thru the openings 28 20 past the flange 29 and around the trap disk 30 into the compartment 34. The latter is filled in a very short time and the shank 35 may then be rotated in an opposite direction to permit the spring 31 to again seat 25 the trap disk 30 upon the face of the flange 29 to close communication between the open compartment 33 and the filling compartment 34. The oil captured within the compartment 34 will then trickle or flow out there- 30 from thru the conical opening 32 to the parts it is desired to lubricate.

I claim:—

1. A lubricating device for musical instruments comprising a sealed casing, a cylinder in said casing having an integral flange, a trap disk in said cylinder seating on said flange separating the latter into two compartments, yieldable means for manu- 45

ally sealing both compartments, and means for opening said compartments. 50

2. A lubricating device for musical instruments comprising a casing, a cylinder in said casing, a trap disk dividing said cylinder into compartments, a spring adapted to yieldably close communication between said compartments, and means lowering said disk for opening communication between said compartments. 55

3. A lubricating device for musical instruments comprising a longitudinal casing, a cylinder in said casing, said instrument having an opening communicating with the bottom of the cylinder, a vertically movable disk dividing said cylinder into compartments, one above the other, a trap disk closing communication between said compartments, yieldable means urging said trap disk to close communication between said compartments, and a threaded shank engaged in said casing passing thru the upper compartment of the cylinder engageable with the trap disk for lowering the same to permit communication between the cylinders. 60

4. A lubricating device for musical instruments comprising a longitudinal casing, a cylinder in said casing, said instrument having an opening communicating with the bottom of the cylinder, a vertically movable disk dividing said cylinder into compartments, one above the other, a trap disk closing communication between said compartments, yieldable means urging said trap disk to close communication between said compartments, a threaded shank engaged in said casing passing thru the upper compartment of the cylinder engageable with the trap disk for lowering the same to permit communication between the compartments, said cylinder having openings communicating with the upper compartment, a flange in said cylinder below the openings and adapted to seat the trap disk for closing communication between the compartments therein. 65

In testimony whereof I affix my signature.

REINHOLD SCHOLZ.
